UNITED STATES PATENT OFFICE.

JAFEW S. VAN BUREN, OF ALBANY, NEW YORK.

DESIGN FOR A FIRE-BRICK.

SPECIFICATION forming part of Design No. 34,105, dated February 19, 1901.

Application filed January 28, 1901. Serial No. 45,149. Term of patent 14 years.

To all whom it may concern:

Be it known that I, JAFEW S. VAN BUREN, a citizen of the United States, residing at Albany, in the county of Albany and State of New York, have invented and produced a new and original Design for a Fire-Brick; and I do hereby declare the following to be a full, clear, and exact description of the same, reference being had to the accompanying drawings, forming a part thereof.

In the accompanying drawings, Figure 1 represents a perspective view of my design. Fig. 2 is a similar view of the opposite side. Fig. 3 is an end view of the same.

My design for a fire-brick consists in the novel shape or configuration of the brick, having one of its vertical faces A provided

with a recess *a*, opening in said face and also on the bottom face B, as shown, having one of its upper corners reduced or cut away, as shown at F, and having its adjacent lower corner D also reduced, the reductions F and D and the recess *a* being the characteristic and essential features of my design.

What I claim, and desire to secure by Letters Patent, is—

The design for a fire-brick herein shown and described.

In testimony whereof I affix my signature in presence of two witnesses.

JAFEW S. VAN BUREN.

Witnesses:

M. BARTLETT,
B. W. DODSON.
